DEWAXING SOLVENT AND SOLVENT
RECOVERY

James V. Montgomery, Okmulgee, and Robert W. Henry, Bartlesville, Okla., assignors to Phillips Petroleum Company, a corporation of Delaware

Application September 25, 1940, Serial No. 358,342

5 Claims. (Cl. 202—39)

This invention relates to mineral oil refining, and more particularly it relates to an improved dewaxing solvent and method of preparing said improved solvent for continued reuse.

It is known to use unsaturated heterocyclic nitrogen bases such as pyridine, picolines, etc., as dewaxing solvents in the refining of mineral oils. Picolines are very effective dewaxing solvents when dry, but they absorb water with avidity and any contamination with water has a deleterious effect on their use as a dewaxing solvent. By continued use of picolines in dewaxing operations, this material soon acquires sufficient water to disrupt normal dewaxing efficiency. When this condition is reached, the picoline solvent must be withdrawn from the dewaxing system and dried. The removal of small quantities of water from a material in which water is very soluble, such as picolines, is frequently an expensive and none too efficient and satisfactory an operation.

An object of this invention is to prepare an improved solvent for dewaxing of lubricating or other oils.

Another object of this invention is to prepare a dewaxing solvent which will be useful even in the presence of small quantities of dissolved water.

Still another object of this invention is to furnish a satisfactory and economic method for the removal of quantities of interfering water from such dewaxing solvents as picolines.

Still other objects and advantages will be apparent from a study of the following disclosure.

We have discovered a dewaxing process involving a method for the convenient and efficient use of picolines or picoline mixtures with other organic solvents and the like. We propose to mix with the picolines certain compounds which increase the solubility of the oil in the solvent mixture, or in other words decreases the miscibility temperature of the oil and solvent to overcome the reverse effects caused by the presence of small quantities of water which accumulate in the solvent; and thereby increase the tolerance of the picolines for water in dewaxing operations. The added material also assists in removing the small quantities of accumulated water from the solvent system, as will be disclosed below.

To satisfy these conditions the added material should have the following characteristics: (1) A lower miscibility temperature with the waxy oil than picolines alone; (2) Complete miscibility with picolines; (3) Relative immiscibility with water; and (4) A boiling point below approximately 200° F. We have found that benzene,

naphtha hydrocarbons of suitable boiling point, the lower ethers such as isopropyl, propyl, ethyl, methyl-ethyl, methyl-propyl, etc., and thioethers of suitable boiling points may be used advantageously with picolines for dewaxing. Furthermore, a process is presented in which any of these added materials may be used as an aid in removing contaminating water from the dewaxing solvent.

The figure illustrates one form of apparatus and one method for carrying out our invention.

Referring to the figure, the oil-solvent mixture, as for example the oil-picoline mixture, or the wax-solvent mixture containing frozen moisture or water from the wax filters passes through line 1 into heater 2 in which the mixture is heated to stripping still temperatures. The heated mixture passes from heater 2 through line 3 into stripping still 4 in which the dewaxing solvent mixture is stripped from the dewaxed oil or wax. Solvent vapors from this stripping still pass overhead through line 5 into condenser 6 in which they are condensed or partly condensed, thence through line 7 and into fractionating tower 8. In fractionator 8 the partially condensed solvent vapors are reboiled sufficiently to remove any water present as vapors of a constant boiling mixture of picolines and water along with vapors of the low boiling added material such as benzene. Water-free, dry picolines exit from fractionator 8 through lines 14 and 15 to run or intermediate storage, not shown. Heat for this reboiling is furnished by passage of the solvent-free dewaxed oil or wax from bottom of stripper 4 through line 36 and into closed reboiler coils 37. From the reboiler coils 37, the stripped oil passes through line 38 to stripped waxed oil storage or stripped wax, not shown.

The mixed vapors, that is picoline-water-constant boiling mixture vapors and benzene vapors pass over head from said fractionator through line 9, are condensed and cooled in condenser 10, pass through lines 11 and 33 into separator 12. Since water is relatively insoluble in liquid benzene, upon condensation of the mixed vapors in 10, two phases separate. These two phases are permitted to settle in separator 12. The upper phase 13 contains the benzene with dissolved picolines, while the lower phase 39 is a water solution of picolines. These two phases separate because of the mutual insolubility of water and benzene. Since picolines are soluble in water and in benzene, layers containing these latter substances dissolve picolines according to the distribution or partition phenomenon. A portion of

the upper phase, that is benzene and picolines, is transferred by pump 34 through line 35 to reflux fractionator 8. The remainder of the benzene-picoline solution leaves the top of the separator 12 through line 16 and joins the dry picolines coming from the bottom of fractionator 8 through line 14, and the combined stream of dry dewaxing solvent passes through line 15 to run storage, not shown, preparatory to reuse.

The lower or picoline-water layer 39 from separator 12 passes through line 17 to run storage 18, from which said water-picoline solution is transferred by pump 19 through line 20 into heating coil 21, thence through line 22 and into fractionator 23. Vapors from the top of this fractionator 23 consist of a constant boiling mixture of picolines and water and are conducted through overhead line 24 into condenser and cooler 25, and the condensed constant boiling mixture is accumulated in receiver 26. A portion of this water-picoline solution is transferred by pump 27 through line 28 to reflux tower 23, while the remainder of said solution leaves accumulator 26 by way of line 30, pump 31, line 32, and joins the liquid in line 11. This combined stream of water-benzene-picolines from line 11 and water-picolines from line 32 enters separator 12 through line 33.

Essentially picoline-free water is removed from the bottom of tower 23 through line 29.

In this above-described manner, the dewaxing solvent is continuously freed of contaminating water by the solvent extraction of picolines from the water-picoline mixture by the benzene to form an essentially dry benzene-picoline solution. The remaining water carries some picolines in solution and these latter are concentrated and recovered as a constant boiling mixture and returned to the system while the water not consumed in forming this constant boiling mixture is withdrawn as essentially picoline-free and benzene-free water.

To those skilled in the art it is obvious that excess drying-miscibility agent, above that desired for miscibility enhancing alone, may be fractionated from the dry solvent mixture before the latter's return to the dewaxing step, the excess being kept recycling in the drying stage.

Though described as particularly adaptable to picolines, we do not wish to be limited by this application since the process may be used equally well with picoline mixtures, pyridine, lutidines, collidines, and their alkyl derivatives, or mixtures of all.

Similarly, benzene has been used throughout our disclosure as the added agent for increasing the tolerance of the picoline solvent for water and as the water removing agent, but we do not desire to be limited to this one material since naphtha hydrocarbons of suitable boiling point, such ethers as iso-propyl, propyl, ethyl, methyl-ethyl, methyl-propyl, etc., and many thio-ethers function equally well.

Likewise, our disclosure describes one method of carrying out our invention, but since various modifications of our disclosed flow chart may be made by those skilled in the art without departing from the spirit of our invention, we do not wish to be limited by the one disclosed example.

We claim:

1. The continuous process of recovering solvent from a dewaxed mineral oil which mineral oil contains traces of water and said water and solvent being mutually soluble and forming a constant boiling point mixture boiling at a tem-

perature below that of water and of the solvent, said solvent being picoline to which has been added an agent which has complete miscibility with the solvent, is relatively immiscible with water and boiling below 200° F., which comprises heating the mixture and passing the same to a first recovery zone, the mineral oil being recovered from the bottom of the first recovery zone and the solvent plus agent and water recovered from the top of the said first recovery zone as a vapor, condensing said vapor and passing the condensate to a second recovery zone, heating said condensate in the second recovery zone, recovering from the bottom thereof a large proportion of the solvent as dry picoline and the vapors passing overhead being condensed and separated into two phases of picoline plus agent and picoline plus water in a third zone, removing the picoline plus agent phase and combining same with the large proportion of dry picoline from the second recovery zone as dried recycle dewaxing solvent, passing the picoline plus water phase to a fourth recovery zone to remove the excess water as bottoms and returning the picoline as a constant boiling point mixture with water therefrom to the third recovery zone.

2. The continuous process of recovering solvent from a dewaxed mineral oil which mineral oil contains traces of water and said water and solvent being mutually soluble and forming a constant boiling point mixture boiling at a temperature below that of water and of the solvent, said solvent being picoline to which has been added an agent such as benzene, which comprises heating the mixture and passing the same to a first recovery zone, the mineral oil being recovered from the bottoms of the first recovery zone and the solvent plus benzene and water recovered from the top of the said first recovery zone as a vapor, condensing said vapor and passing the condensate to a second recovery zone, heating said condensate in the second recovery zone, recovering from the bottom thereof a large proportion of the solvent as dry picoline and the vapors passing overhead being condensed and separated into two phases of picoline plus benzene and picoline plus water in a third zone, removing the picoline plus benzene phase and combining same with the large proportion of dry picoline from the second recovery zone as dried recycle dewaxing solvent, passing the picoline plus water phase to a fourth recovery zone to remove the excess water as bottoms and returning the picoline as a constant boiling point mixture with water therefrom to the third recovery zone.

3. The continuous process of recovering solvent from a dewaxed mineral oil which mineral oil contains traces of water and said water and solvent being mutually soluble, said solvent being an unsaturated heterocyclic nitrogen base to which has been added an agent which has complete miscibility with the solvent, is relatively immiscible with water and boiling below 200° F., which comprises heating the mixture and passing the same to a first recovery zone, the mineral oil being recovered from the bottom of the first recovery zone and the solvent plus agent and water recovered from the top of the said first recovery zone as a vapor, condensing said vapor and passing the condensate to a second recovery zone, heating said condensate in the second recovery zone, recovering from the bottom thereof a large proportion of the solvent as dry heterocyclic nitrogen base and the vapors passing overhead being condensed and separated into two

phases of heterocyclic nitrogen base plus agent and heterocyclic nitrogen base plus water in a third zone, removing the heterocyclic nitrogen base plus agent and combining same with the large proportion of dry heterocyclic nitrogen base from the second recovery zone as a dried recycle dewaxing solvent, passing the heterocyclic nitrogen base plus water phase to a fourth recovery zone to remove the excess water as bottoms, and returning the heterocyclic nitrogen base as a constant boiling mixture with water therefrom to the third recovery zone.

4. The continuous process of recovering solvent from a dewaxed mineral oil which mineral oil contains traces of water and said water and solvent being mutually soluble and forming a constant boiling point mixture boiling at a temperature below that of water and of the solvent, said solvent being a picoline mixture to which has been added an agent such as benzene, which comprises heating the mixture and passing the same to a first recovery zone, the mineral oil being recovered from the bottoms of the first recovery zone and the solvent plus benzene and water recovered from the top of the said first recovery zone as a vapor, condensing said vapor and passing the condensate to a second recovery zone, heating said condensate in the second recovery zone, recovering from the bottom thereof a large proportion of the solvent as a picoline mixture and the vapors passing overhead being condensed and separated into two phases of picoline mixture plus benzene and picoline mixture plus water in a third zone, removing the picoline mixture plus benzene phase and combining same with the large proportion of dry picoline mixture from the second recovery zone as dried recycle dewaxing solvent, passing the picoline mixture

plus water phase to a fourth recovery zone to remove the excess water as bottoms and returning the picoline mixture as a constant boiling point mixture with water therefrom to the third recovery zone.

5. The continuous process of recovering solvent from a dewaxed mineral oil which mineral oil contains traces of water and said water and solvent are mutually soluble, said solvent being a picoline mixture to which has been added an agent which has complete miscibility with the solvent, is relatively immiscible with water and boiling below 200° F., said agent being a petroleum hydrocarbon fraction boiling below 200° F., which comprises heating the mixture and passing the same to a first recovery zone, the mineral oil being recovered from the bottom of the first recovery zone and the solvent plus agent and water recovered from the top of said first recovery zone as a vapor, condensing said vapor and passing the same to a second recovery zone, heating the condensate in the second recovery zone, recovering from the bottom thereof a large proportion of the solvent as dry picoline mixture and the vapors passing overhead being condensed and separated into two phases of picoline mixture plus agent and picoline mixture plus water, passing the two phases to a third or stratification zone, removing the picoline mixture plus agent phase from said third zone, passing the water plus picoline mixture phase to a fourth recovery zone to remove the excess water and returning the remainder of the water plus picoline mixture as a constant boiling mixture from the fourth recovery zone to the third recovery zone.
